CLAIM

I claim the ornamental design of the furniture console, as shown and described.

DESCRIPTION

FIG. 1 is a downward rightward frontward perspective view of a furniture console according to my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left elevational view thereof; and,

FIG. 7 is a right elevational view thereof.
